HOBBYHORSE

George J. Brown, Chicago, Ill.

Application December 5, 1945, Serial No. 632,846

11 Claims. (Cl. 272—52)

1

The invention relates to toys and has for an object to provide a toy hobby horse of improved design having resilient steel rockers and a seat pivotally secured to the rockers for attaining maximum riding comfort.

Another object of the invention resides in the provision of a hobby horse having steel rockers of resilient metal and which additionally form a foot support for the occupant.

Another object is to provide a hobby horse having a floating seat due to the pivotal connection of the seat to the resilient metal rockers, and wherein the metal rockers have a front and rear formation for limiting the extent of the rocking movement.

With these and various other objects in view the invention may consist of certain novel features of construction and operation as will be more fully described and particularly pointed out in the specification, drawings and claims appended hereto.

In the drawings which illustrate an embodiment of the invention and wherein like reference characters are used to designate like parts—

Figure 1 is a perspective view of the hobby horse embodying the improvements of the invention;

Figure 2 is a front elevational view of the hobby horse shown in Figure 1;

Figure 3 is a top plan view; and

Figure 4 is a bottom plan view.

For illustrating the invention a preferred embodiment of the hobby horse has been shown in Figure 1, the same including a seat 10 having a rear seating portion 11 and a forward portion 12 for supporting the head piece 13. The head piece is suitably secured to the portion 12 of the seat substantially centrally thereof and said head piece is preferably shaped and painted to simulate a horse. Handles 14 are provided so that the occupant of the hobby horse may grip the head piece and thus assist in the rocking movement. The said handles may comprise a rod, as shown, extending through the head piece 13 at the desired location so as to project from opposite sides thereof. For retaining the occupant on the seat 10 the same is provided with a metal guard rail 15 which has encircling relation with the seat at the proper elevation above the same. The forward portion of the guard rail is secured to the head piece 13 by means of the metal strap 16. Additional supports for the guard rail are provided, however, in the form of metal uprights 17, 18 and 19, which are secured at their upper end to the guard rail and at their lower end the

2

same are bent to extend under the seat 10. Metal straps 20 fixedly secure the said lower bent ends of the uprights to the undersurface of the seat.

The rockers for the hobby horse comprise resilient steel tubing which has been shaped to provide foot supports in addition to forming the rockers for the horse. A pair of rockers 21 and 22 are provided and which are convex, as best shown in Figure 1, to effect the desired back and forth rocking movement of the hobby horse. Each rocker at its forward end has a special formation, indicated by numeral 23, to form a stop or bumper as regards the rocking movement in a forward direction. A similar stop or bumper 24 is provided at the rear end of each rocker for limiting in a similar manner rocking movement in a rearward direction.

Referring again to the forward end, the metal tubing of each rocker is bent upon itself to form the curve 25 and the same extends rearwardly in a diagonal upward direction, whereupon another bend, indicated by numeral 26, Figure 2, for each rocker is provided for the purpose of forming the foot supports 27. Two such supports are accordingly provided at the proper distance below and in a direction forwardly of the seat 10. Each foot support is terminated by the inner bend 28 and the steel tubing then extends upwardly in a diagonal direction forming the portions 29 which are joined, providing the arcuate section 31. This arcuate section is rotatably secured to the undersurface of the seat 10 in the vicinity of the forward portion 12 thereof by means of the clamp 32.

Referring to the rear of the rockers, it will be observed that the metal tubing of each rocker is bent upon itself to form the curve 33 and from the curve each length of metal tubing has a slight downward bow, as best shown in Figure 1, and is also bowed inwardly, as illustrated in Figures 3 and 4. These rear sections, indicated by numeral 34, are joined by the straight horizontal section 35, Figure 4, which has location under seat 10 and adjacent the seating portion 11 thereof. Section 35 is rotatably secured to the seat by the clamps 36.

The occupant of the present hobby horse can impart a bouncing effect to the same as well as a rocking motion since the resiliency and shape of the rockers makes both movements possible. During the rocking of the hobby horse the seat has a floating action since the clamps 32 and 36 are fixed to the seat so as to rotatably secure the respective ends of the rockers. Also a more

realistic riding action results by reason of this pivoting of the seat on the rockers. The integral foot supports provided by the rockers respectively are thus held to the seat and maintained at the same distance from the seat irrespective of the motion of the hobby horse. Another improved feature resides in the bumpers at each end of the rockers for limiting forward and rearward rocking motion. The bumpers perform their limiting action in a manner which effectively relieves the shock resulting therefrom so that very little, if any, is transmitted to the occupant.

The invention is not to be limited to or by details of construction of the particular embodiment thereof illustrated in the drawings, as various form of the device will of course be apparent to those skilled in the art without departing from the spirit of the invention or the scope of the claims.

What is claimed is:

1. In a toy hobby horse, in combination, a seat, and a pair of rockers of resilient material secured to said seat, said rockers having pivotal securing to the seat at the forward end of the seat and at the rearward end of the seat respectively, and said rockers having a formation to provide foot supports for the occupant of the hobby horse.

2. In a toy hobby horse, in combination, a seat, a member fixed to the seat and extending above and forwardly of the seat, and a pair of rockers of resilient metal secured to the underside of the seat, said rockers having a pivotal securing to the seat at the forward end of the same and at the rearward end of the seat respectively, and said rockers having a formation to provide foot supports for the occupant of the hobby horse.

3. In a toy hobby horse, in combination, a seat, a pair of rockers of resilient metal secured to said seat, said rockers each having a forward leg pivotally secured to the forward end of the seat and each having a rear leg pivotally secured to the rear end of the seat, and the forward leg of each rocker having a formation to provide a foot support.

4. In a toy hobby horse, in combination, a seat, a member fixed to the seat and extending above and forwardly of the seat, a pair of rockers of resilient metal secured to the seat for supporting the same and which permit rocking movement in a forward and rearward direction, said rockers each having a forward leg pivotally secured to the forward end of the seat and each having a rear leg pivotally secured to the rear end of the seat, and the forward leg of each rocker having a formation intermediate the ends thereof to provide a foot support.

5. A toy hobby horse as defined by claim 2, wherein the member fixed to the seat provides a pair of handles for the occupant of the hobby horse.

6. A toy hobby horse as defined by claim 4, wherein the member fixed to the seat provides a pair of handles for the occupant of the hobby horse.

7. In a toy hobby horse, in combination, a seat, a pair of rockers of resilient material secured to the seat for supporting the same and which permit rocking movement in a forward and rearward direction, each rocker having a front and a rear leg respectively, the front leg of each rocker having a formation to provide a foot support, and both legs of each rocker having a formation at the lower end thereof to provide a bumper for limiting said rocking movement.

8. In a hobby horse, in combination, a seat, a pair of rockers of resilient metal secured to the seat for supporting the same and which permit rocking movement in a forward and rearward direction, said rockers each having a forward leg pivotally secured to the forward end of the seat and each having a rear leg pivotally secured to the rear end of the seat, the front leg of each rocker having a formation to provide a foot support, and both legs of each rocker having a formation at the lower end thereof to provide a bumper for limiting said rocking movement.

9. In a toy hobby horse, a seat, a head piece fixed to the seat and extending above and forwardly of the seat, a pair of rockers of resilient metal for supporting the seat, said rockers each including an intermediate rocking portion of convex shape and front and rear leg portions integral therewith, said intermediate rocking portions permitting rocking movement in a forward and rearward direction, means pivotally securing the leg portions of each rocker to the seat, the front leg portion of each rocker having a formation to provide a foot support, and each rocker at the respective ends of the rocking portion and between the same and its leg portions having a shape to form a bumper for limiting rocking movement of the hobby horse.

10. A rocking toy, comprising in combination two opposed rockable body members, each of the body members formed of a single length of metal bent to form a top portion, inclined end portions, a bottom portion, and a stirrup portion, and a saddle member mounted on the body members.

11. A rocking toy, comprising in combination two opposed rockable body members, each of the body members formed of a single length of metal bent to form a horizontal top portion, inclined front and rear end portions, a curved bottom portion and a lateral stirrup portion, and a saddle member mounted on the body members.
